W. H. DE FONTAINE & W. H. DE FONTAINE, JR.
LIFE PRESERVER.
APPLICATION FILED MAY 27, 1918.

1,290,927.

Patented Jan. 14, 1919.

FIG. 1.

FIG. 2.

UNITED STATES PATENT OFFICE.

WADE HAMPTON DE FONTAINE AND WADE HAMPTON DE FONTAINE, JR., OF NEW YORK, N. Y.

LIFE-PRESERVER.

1,290,927.

Specification of Letters Patent. Patented Jan. 14, 1919.

Application filed May 27, 1918. Serial No. 236,705.

To all whom it may concern:

Be it known that we, WADE HAMPTON DE FONTAINE, a citizen of the United States, and a resident of the borough of Manhattan, 5 city, county, and State of New York, and WADE HAMPTON DE FONTAINE, Junior, a citizen of the United States, and a resident of the borough of Bronx, city of New York, county of Bronx, and State of New York, 10 have jointly invented certain new and useful Improvements in and Relating to Life-Preservers, of which the following is a full, clear, concise, and exact description, such as will enable others skilled in the art to which 15 our invention relates to make and use the same, reference being made therein to the accompanying drawing, which forms a part of this specification.

Our invention relates to life preservers 20 of the type or class having a hollow collapsible and inflatable supporting member, together with means for supplying gas to the interior of said member to thereby inflate and expand the same and render it buoyant, 25 because of the volume of water displaced by it; and particularly to life preservers of the type or kind above referred to and in which the operation of the inflating means, device, or mechanism is dependent upon the action 30 of the water in which the preserver floats; so that the inflation of the inflatable member will take place when the preserver reaches the water, and is brought about by the action of the water upon some element or device 35 present in and forming a part thereof.

The object of our invention is to provide 40 a life preserver of the general type above referred to and one in which the inflation of the inflatable member is entirely automatic, and requires no act whatever on the part of 45 the wearer in order to insure the inflation of said member; so that should a person wearing a preserver made in accordance with our invention suffer injury, become bewildered, 50 or be otherwise incapacitated from acting during the confusion ordinarily incident to the sinking or to serious injury inflicted upon or suffered by a vessel, then and in that event the inflatable member of the preserver 55 will, upon the falling of the person wearing the same into the water, be automatically inflated and the preserver rendered effective to sustain him in the water, and that without the performance by him of any act or operation whatever thereupon.

A further object of our invention is to provide a life preserver of the type in question in which the means for accomplishing the inflation of the inflatable member is in the form of a single unitary device or structure, 60 and is entirely independent of the specific form, shape, or other characteristics of the inflatable member; so that inflating mechanism of one standard form and construction may be used with inflatable members of 65 various shapes and forms, and with inflatable members adapted to be secured to and worn in various positions upon the body of the user.

A further object of our invention is to provide a life preserver having the features above enumerated and one which will be simple in construction, reliable in its operation, and effective for the purpose for which it is designed, and which may be manufactured and assembled and made ready for use, 70 at a minimum of expense.

With the above and other objects of invention in view, our invention consists in the improved life preserver illustrated in 75 the accompanying drawing and hereinafter described and claimed, and in such variations and modifications thereof as will be obvious to those skilled in the art to which our invention relates.

In the drawing accompanying and forming a part of this specification, and wherein the preferred embodiment of our invention is illustrated:

Figure 1 is a view showing our invention 90 as applied to an ordinary form of life preserver, in the form of a belt designed to extend about the body of a user;

Fig. 2 is a view upon a considerably enlarged scale showing the gas generating 95 mechanism by itself, a portion of the casing thereof being broken away to show features of internal construction;

Fig. 3 is a view showing a section upon a plane indicated by the line 3—3 of Fig. 2; 100 and

Fig. 4 is a view similar to Fig. 3 but showing the parts in another position.

Referring now to the drawing, Fig. 1 illustrates a complete life preserver made in accordance with our invention, while Figs. 2, 3 and 4 illustrate the gas generating mechanism thereof by itself, and unconnected with the hollow inflatable member designed to be secured to a person; it being expressly un- 105 110

derstood that our invention includes gas generating mechanism *per se*, and apart from an inflatable member, as well also as the combination of a gas generating device 5 and an inflatable member; and that the gas generating mechanism as a unitary structure may be secured to any kind of a hollow inflatable member, and to inflatable members designed to be secured to or worn in various 10 positions by and upon the person of the user of the device.

In Fig. 1 the gas generating mechanism is shown as secured to and carried by a hollow inflatable member 3 in the form of a 15 belt designed to extend about the body of the wearer, and the ends of which are secured together in any way as by means of the fastening members 4, 5; the gas generating device as a whole and indicated in this 20 figure by the reference numeral 6, being shown upon a larger scale in Figs. 2, 3 and 4.

Referring now to Figs. 2 to 4, the reference numeral 7 designates a portion of the wall of a hollow inflatable member, the same 25 being provided with an opening within which the gas generating mechanism is secured; the said gas generating mechanism having a closed casing within which the various elements thereof are contained; and 30 which casing is made up of an inner casing member 8, an outer annular casing member 9, and a cover 10 closing the central opening in the annular casing member; said casing members being secured together and in place 35 in the opening in the wall 7 by screws 11 extending through holes in the casing members and into threaded openings provided in a ring 12 between which and a flange on the inner casing member the edge of the 40 inflatable member is clamped, in the embodiment of our invention illustrated; a gasket 13 being interposed between the meeting edges of the peripheries of the casing members in order to secure a tight joint between 45 the parts, as will be appreciated.

The cover 10 is provided with a depending annular portion or flange 14 which is in threaded engagement with an opening provided in the annular casing member 9, and 50 the inner end 15 of this depending portion forms a valve seat (referred to hereinafter and in various of the concluding claims as a second valve seat), and a plurality of holes 16 are provided in said cover through which 55 water may flow when the preserver comes into contact with the water; the holes forming a normally open water inlet passage through which water may flow into the interior of the casing of the gas generating 60 device, and which passage extends past and is surrounded by the valve seat 15, as will be appreciated. Said cover 10 is also provided with a strut member 17 which serves as a guide for and as a part of locking mechanism associated with and adapted to hold a 65

valve located within the casing upon its seat, as will hereinafter appear.

The inner casing member 8 is so shaped as to provide a chamber 18 adapted to contain a substance which will generate a gas when 70 water comes into contact therewith, such, for example, as calcium carbide; the said chamber being located in line and concentric with the opening into which the cover 10 fits, and the same being annular in form in the embodiment of our invention illustrated; and the inner of the concentric walls 19, 20 of the said chamber forms a gas outlet passage through which gas may flow from the interior of the casing into the hollow inflatable 80 member to thereby dilate the same. The particular form and location of the chamber in question, as well as the form and location of the gas outlet passage are, however, of secondary importance, and may be varied 85 within the scope of the concluding claims wherein the features of our invention here referred to are enumerated. The inner casing member is also provided with a valve seat 21 surrounding the inlet leading into 90 the chamber 18; and beyond the said valve seat the wall of the casing is shown as so shaped as to provide an annular channel 22, the purpose of which is to provide ample water receiving space within the casing so 95 that when the valve next referred to moves from its seat, and the generation of gas commences, there will be a sufficient supply of water within the casing to carry on the generation of the gas and to secure the production of a quantity thereof sufficient to accomplish the proper inflation of the hollow inflatable member.

Located within the casing of the gas generating mechanism is a valve 23 which, in effect, forms a cover or closure for the inlet to the carbide containing chamber 18, the periphery of said valve seating upon the valve seat 21 and thus preventing the entrance of water into said chamber until the 105 valve shall have moved off its seat; and which valve also serves to seal the contents of the said chamber and prevent access of air carrying moisture thereto which, if not prevented, would tend to cause a gradual 110 generation of gas due to the slow decomposition of the carbide caused by the presence of moisture in the air. This sealing of the contents of the chamber which contains the gas generating material is the more perfectly accomplished in the form of our invention illustrated in which the gas outlet passage from the interior of the casing in fact leads from the carbide chamber, by providing a second valve 24, which is secured to 115 and moves with the valve 23 and seats upon the upper end of the inner annular wall 20 which forms the gas outlet passage.

The valve designated as a whole by the reference numeral 23 is preferably made up 120

of spaced upper and lower plates 25, 26 between which a flexible soft rubber disk 27 is clamped, and the valve 24 which is also of soft rubber rests against the lower of said disks. The disks and the two valves are held together by a centrally located tubular sleeve or guide 28 extending through openings provided in said members and having a shoulder against which the upper disk abuts, 5 and a washer 29 at its lower or inner end; said guide having a central passage into which the free end of the strut member 17 extends whereby said valve is guided by the said strut member when it moves from its seat, as will be understood. The valve 23 is acted upon by a spring which tends to move it off its seat and which, in the embodiment of our invention illustrated, is located within the carbide chamber 18 and 10 rounds the inner annular wall 20 thereof, and to which spring the reference numeral 30 is applied.

The valve 23 is held in place upon the seat 21, thus sealing the contents of the chamber 18, by means dependent upon and 15 controlled by a soluble member located within the casing of the gas generator in the embodiment of our invention illustrated, and which holding means when released by 20 the action of water upon the soluble member releases the valve and permits the spring 30 to move the same away from the seat 21 and into contact with the second seat 15, to thereby arrest the flow of water into the 25 casing and permit the water which has already entered thereinto to come into contact with the gas generating substance or material contained in the chamber 18; the 30 preferred form of holding, locking, and releasing mechanism and the operation thereof to accomplish the results enumerated being as follows: The upper of the valve disks 23 carries a movable locking member shown as 35 in the form of a U-shaped spring 31 one end 40 of which is secured in an abutment 32 struck up from the material of the disk and bent down over the spring, as shown in Figs. 3 and 4, and which spring extends about a 45 guide 33 also struck up from the disk; the 50 free end of said spring which forms a movable locking member lying in a recess 34 provided in the tubular guide 28, and the said end being normally in line with the end of the strut 17. The said free end of the movable locking member is held in the normal 55 locking position in which it is shown in Figs. 2 and 3 by a soluble member 35 carried by the disk 23 and held in place by an abutment 36 thereupon. When, however, water 60 entering the casing has dissolved the said soluble member, which may be a block of sugar or any other suitable soluble substance, or weakened it to such an extent that the force of the spring 31 may crush it, then 65 the locking member will move out of the

recess 34 and away from in front of the end of the strut 17, and the spring 30 will move the valve 23 off its seat as hereinbefore explained; it being understood that the valve in question is normally closed on to the seat 70 21, and that the locking member or spring 31 normally lies opposite the end of the strut 17 to thereby lock the valve in place upon its seat.

In view of the premises it will be appreciated 75 that should a person wearing a life preserver equipped with or made in accordance with our invention fall, jump or be thrown into the water, perhaps in an injured or unconscious condition, water will 80 flow through the inlet openings 16 and into the interior of the casing formed by the casing members 8 and 9 and the cover 10, and the soluble member 35 will be wetted and dissolved or weakened to such a degree 85 that it will be crushed by the action of the resilient member 31; whereupon the locking member will be moved out of the recess in the tubular member 28 and away from its normal position in line with the strut 90 member 17. This action releases the valve 23 from the locking action of the strut 17 and movable locking member normally lying opposite its free inner end, and permits the spring 30 to move the said valve away 95 from the valve seat 21 and into engagement with the second valve seat 15, thus arresting the flow of water into the casing.

Before the upward movement of the valve 23 occurs, however, a considerable quantity 100 of water will have entered the casing, or at least a quantity sufficient for the end to be accomplished, the interior of the casing being quite roomy and additional water receiving and holding capacity being provided 105 for by the annular groove 22. When the said valve moves from its seat it uncovers the mass of calcium carbide or other gas generating material contained within the chamber 18, and the water present within the 110 casing is thus permitted to come into contact with the gas generating material; whereupon a gas is produced which flows through the gas outlet passage formed by the wall 20 and into the interior of the hollow inflatable member, thus inflating and distending it in a manner which is entirely automatic, and without any attention on the part of the wearer or the performing by him of any 115 act or operation whatever upon the preserver 120 or upon the mechanism thereof whereby the gas for inflating the same is generated or produced.

The seating of the valve 23 upon the second valve seat 15 resulting from the movement imparted to the valve by the spring 30 in addition to arresting the flow of water 125 into the casing, prevents the flow of gas therefrom; and the force with which the valve is pressed against this last mentioned 130

seat obviously increases as the generation of gas proceeds, and is the greater the greater the pressure of the gas within the hollow inflatable member is, as will be appreciated.

5 Having thus described and explained our invention, we claim and desire to secure by Letters Patent—

1. In a device of the class described, a hollow inflatable member; a casing carried 10 by said member and having a normally open water inlet passage, a chamber adapted to contain a gas generating substance, and a gas outlet passage through which gas may flow into said inflatable member; a valve 15 seat extending about the inlet leading into said chamber; a valve within said casing and adapted to seat upon said valve seat to thereby prevent the entrance of water into said chamber; a spring acting upon said 20 valve and tending to move it off its seat; means for holding said valve in place upon its seat; and locking means coöperating with said holding means and adapted to be held in its normal locking position by a soluble 25 member located within said casing.
2. In a device of the class described, a hollow inflatable member; a casing carried by said member and having a normally open water inlet passage, a chamber adapted 30 to contain a gas generating substance, and a gas outlet passage through which gas may flow into said inflatable member; a valve seat extending about the inlet to said chamber; a valve within said casing and adapted 35 to seat upon said valve seat to thereby prevent the entrance of water into said chamber; a spring acting upon said valve and tending to move it off its seat; and means controlled by a soluble member within said 40 casing for holding said valve upon its seat, and for releasing said valve and permitting said spring to move the same off its seat when water has acted upon said soluble member.
- 45 3. In a device of the class described, a hollow inflatable member; a casing carried by said member and having a normally open water inlet passage, a chamber adapted to contain a gas generating substance, and a 50 gas outlet passage through which gas may flow into said inflatable member; a valve seat surrounding the inlet to said chamber; a valve within said casing and adapted to seat upon said valve seat to thereby prevent the 55 entrance of water into said chamber; a spring acting upon said valve and tending to move it off its seat; a strut carried by the wall of said casing and extending toward said valve; a resilient locking member carried by said 60 valve; and a soluble member carried by said valve and adapted to hold said resilient member in place between the end of said strut and the said valve to thereby prevent movement of the valve away from its seat.
- 65 4. In a device of the class described, a cas-

ing having an opening leading thereinto, a chamber located in line with said opening and adapted to contain a gas generating substance, and a gas outlet passage; a perforated cover for closing said opening; a valve seat surrounding the inlet leading into said chamber; a valve within said casing and adapted to seat upon said valve seat; a spring acting upon said valve and tending to move it off its seat; a tubular guide 70 carried by said valve; a strut carried by said cover and extending into said tubular guide; a resilient locking member carried by said valve and lying within a recess provided in said guide and in line with the end of said strut to thereby hold said valve upon its seat; and a soluble member carried by said valve and adapted to hold said locking member within said recess and in line with the end of said strut.

5. In a device of the class described, a casing having a circular opening leading thereinto, an annular chamber concentric and located in line with said opening and adapted to contain a gas generating substance, and a 90 gas outlet passage surrounded by said annular chamber; a perforated cover for closing said opening; a valve seat surrounding the inlet leading into said chamber; a valve within said casing and adapted to seat upon said 95 valve seat to thereby prevent the entrance of water into said chamber; a spring within said annular chamber and surrounding the gas outlet passage aforesaid, and which spring tends to move said valve off its seat; a tubular guide carried by said valve; a strut carried by said cover and extending into said tubular guide; a resilient locking member carried by said valve and lying within a recess provided in said guide and in 100 line with the end of said strut to thereby hold said valve upon its seat; a soluble member carried by said valve and adapted to hold said locking member within said recess and in line with the end of said strut; and a second valve carried by said first mentioned valve and adapted to close the gas outlet passage aforesaid when said first mentioned valve is upon its seat.

6. In a device of the class described, a casing having a normally open water inlet passage, a chamber adapted to contain a gas generating substance, and a gas outlet passage; a valve seat surrounding the inlet leading into said chamber; a valve within said casing and adapted to seat upon said valve seat to thereby prevent the entrance of water into said chamber; means acting upon said valve and tending to move it off its seat; and means controlled by a soluble member within 115 said casing for holding said valve upon its seat, and for releasing said valve so that it may move from its seat when water has acted upon said soluble member.

7. In a device of the class described, a 130

1. Casing having a normally open water supply passage, a chamber adapted to contain a gas generating substance, and a gas outlet passage; a valve seat surrounding said chamber; a valve within said casing and adapted to seat upon said valve seat to thereby prevent the entrance of water into said chamber; a spring acting upon said valve to move it off its seat; and means controlled 5 by a soluble member for holding said valve upon its seat, and for releasing said valve so that said spring may move it from its seat when water has acted upon said soluble member.
2. In a device of the class described, a casing having a normally open water inlet passage, a chamber adapted to contain a gas generating substance, and a gas outlet passage; a valve seat surrounding the inlet leading into said chamber; a valve within said casing and adapted to seat upon said valve seat to thereby prevent the entrance of water into said chamber; a spring acting upon said valve and tending to move it off its seat; a strut extending from the wall of said casing toward said valve; a movable locking member interposed between said valve and the end of said strut; means tending to move said locking member from its normal position between the said valve and the end of said strut.
3. In a device of the class described, a casing having a circular opening leading thereinto, an annular chamber concentric and located in line with said opening and adapted to contain a gas generating substance, and a gas outlet passage formed by the inner of the two walls of said annular chamber; a perforated cover for closing said opening; a valve seat surrounding the inlet leading into said chamber; a valve within said casing and adapted to seat upon said valve seat to thereby prevent the entry of water into said chamber; a spring acting upon said valve and tending to move it off its seat; a tubular guide carried by said cover; a strut carried by said cover and extending into said tubular guide; a movable locking member lying within a recess provided in said guide and in line with the end of said strut; means tending to move said locking member out of its normal position within said recess; and a soluble member adapted to hold said locking member in its normal position within said recess.
4. In a device of the class described, a casing having a normally open water supply passage, a chamber adapted to contain a gas generating substance, and a gas outlet passage; a valve seat surrounding the inlet leading into said chamber; a valve within said casing and adapted to seat upon said
5. valve seat to thereby prevent the entrance of water into said chamber; means acting upon said valve and tending to move it off its seat; means controlled by a soluble member within said casing for holding said valve upon its seat, and for releasing said valve so that it may be moved from its seat when water has acted upon said soluble member; and a second valve carried by said first mentioned valve and adapted to close the gas outlet passage aforesaid when said first mentioned valve is upon its seat.
6. In a device of the class described, a casing having a normally open water inlet passage, an annular chamber adapted to contain a gas generating substance, and a gas outlet passage provided by the inner one of the walls of said annular chamber; a valve seat surrounding the inlet leading into said chamber; a valve within said casing and adapted to seat upon said valve seat to thereby prevent the entrance of water into said chamber; means acting upon said valve and tending to move it off its seat; means controlled by a soluble member within said casing for holding said valve upon its seat, and for releasing said valve so that it may be moved from its seat when water has acted upon said soluble member; and a second valve carried by said first mentioned valve and adapted to close the gas outlet passage aforesaid when said first mentioned valve is upon its seat.
7. In a device of the class described, a casing having a normally open water supply passage, a chamber adapted to contain a gas generating substance, and a gas outlet passage; a valve seat surrounding said chamber; a valve within said casing and adapted to seat upon said valve seat to thereby prevent the entrance of water into said chamber; a spring acting upon said valve to move it off its seat; means controlled by a soluble member for holding said valve upon its seat, and for releasing said valve so that said spring may move it from its seat when water has acted upon said soluble member; and means whereby the flow of water through said water supply passage and into said casing is arrested when said valve is moved from its seat by said spring.
8. In a device of the class described, a casing having a normally open water inlet passage, a chamber adapted to contain a gas generating substance, and a gas outlet passage; a valve seat surrounding the inlet leading into said chamber; a valve within said casing and adapted to seat upon said valve seat to thereby prevent the entrance of water into said chamber; a spring acting upon said valve and tending to move it off its seat; a strut extending from the wall of said casing toward said valve; a movable locking member carried by said valve and normally lying in line with the end of said

strut; means tending to move said locking member from its normal position to thereby permit said spring to move said valve off its seat; a soluble member carried by said 5 valve and adapted to hold said locking member in its normal position; and a second valve seat against which said valve is moved by said spring after it is released from the holding action of said locking member, as 10 aforesaid, to thereby arrest the flow of water into said casing.

14. In a device of the class described, a casing having a circular opening leading thereinto, an annular chamber concentric 15 and located in line with said opening and adapted to contain a gas generating substance, and a gas outlet passage formed by the inner of the two walls of said annular chamber; a perforated cover for closing said 20 opening; a valve seat surrounding the inlet leading into said chamber; a valve within said casing and adapted to seat upon said valve seat to thereby prevent the entry of water into said chamber; a spring acting 25 upon said valve and tending to move it off its seat; a tubular guide carried by said valve; a strut carried by said cover and extending into said tubular guide; a movable locking member lying within a recess provided in said guide and in line with the end 30 of said strut; means tending to move said locking member out of its normal position within said recess; a soluble member adapt-

ed to hold said locking member in its normal position within said recess; and a second 35 valve seat formed by and upon a depending annular flange whereby said cover is secured in place, and into engagement with which said valve is moved by said spring after it has been released from the holding action of 40 said locking member.

15. In a device of the class described, a casing having a normally open water supply passage, a chamber adapted to contain a gas generating substance, and a gas outlet passage; a valve seat surrounding said chamber; a valve within said casing and adapted to seat upon said valve seat to thereby prevent the entrance of water into said chamber; a spring acting upon said valve to move it 45 off its seat; means controlled by a soluble member for holding said valve upon its seat, and for releasing said valve so that said spring may move it from its seat when water has acted upon said soluble member; and a second valve seat past which water flowing through said water supply passage flows, and against which said valve is moved by said spring after it has been released as 50 aforesaid, to thereby arrest the flow of water 55 into said casing.

In testimony whereof we have signed our names to this specification at New York, New York, this 23d day of May, 1918.

WADE HAMPTON DE FONTAINE.

WADE HAMPTON DE FONTAINE, JR.
